BLOCK LIFTER

Jacob D. Naillon, Oakland, Calif.

Application December 1, 1947, Serial No. 789,014

18 Claims. (Cl. 294—63)

1

This invention relates to the art of handling materials, and, more particularly, to a lifter or loader for picking up and changing the spacing of blocks, such as bricks, boxes and the like. The invention finds especial application in the handling of objects which are manufactured in standardized or uniform sizes and are stacked in regular patterns, such as concrete masonry, but is not limited thereto, being useful also for handling any objects which can be clamped.

The invention is, more particularly, concerned with an improved clamping device for clamping a block or a row of blocks between gripping jaws; and with a lifting device wherein a series of clamping frames provided with such gripping jaws are mounted for longitudinal motion, whereby each of such frames may be clamped to one or more blocks and the interval between such blocks may be altered by moving the loaded frames on the supporting structure.

The embodiment of the invention described in this specification is designed particularly for handling concrete masonry bricks which have been stacked in a storage yard by the telescoping carrier described in my copending application Ser. No. 772,772, filed September 8, 1947. The carrier disclosed in said application deposits concrete masonry bricks in the storage yard in eighteen vertical tiers of bricks, each tier containing a plurality of bricks, e. g., six to twelve, depending upon the sizes of the bricks. The tiers of bricks are arranged on the ground in parallel rows or ranks containing six tiers of bricks, the tiers in each row being without horizontal intervals, or substantially without such intervals. The rows, however, are spaced one from the other so that a small longitudinal interval, usually about two inches, is provided between the bricks. The carrier according to the aforesaid application deposits three rows of tiers in one operation, i. e., 108 bricks when the tiers contain six bricks. Successive rows are deposited in successive operations in a manner to maintain the same, uniform longitudinal spacing between the transverse rows to form a composite stack of any desired length. In the aforesaid application the individual bricks are arranged with their longest dimensions disposed parallel to the length of the composite stack, i. e., perpendicular to the transverse rows; when "half size" bricks are handled, e. g., concrete masonry bricks having dimensions of 4 in. x 8 in. x 16 in., the smallest dimensions are vertical. However, the instant invention is not limited to any specific orientation of the bricks.

It is an object of this invention to provide a

2

block lifting device suitable for clamping and lifting blocks, such as concrete masonry bricks, which have been stacked in the manner described in the foregoing paragraph, and which can decrease the longitudinal interval between the blocks. More particularly, it is an object to provide a block loader for picking up a number of bricks from a stack of the type described and loading them on a truck, pallet, or other vehicle without horizontal intervals between bricks.

Another general object of this invention is to provide a block lifting device for clamping and lifting a plurality of blocks which have been stacked in a regular pattern, viz., a rectilinear pattern.

Still another object is to provide a block lifter which is adapted to clamp a plurality of bricks or a plurality of rows of bricks or a plurality of tiers of bricks or a plurality of rows of tiers of bricks which are initially spaced with longitudinal spaces between bricks, and which lifter is adapted to reduce or eliminate said spaces, whereby the bricks can be deposited in the same or in another location in a more compact stack.

Still another object is to provide a clamping mechanism for a block lifter provided with gripping jaws wherein the gripping jaws are self-clamping or self-locking, and wherein the clamp actuating mechanism is of simple construction.

A further object is to provide a block-clamping device wherein gripping jaws for clamping one or more blocks are supported from a frame by supports urging the jaws closer together as the jaws are moved relatively to the frame by the load, and the jaws are urged apart by said support when the jaws are moved relatively to the frame in the opposite direction, whereby the weight or drag on the block tends to clamp the jaws together and a simple shifting of the jaws releases the block.

Still a further object is to provide an improved and simplified clamp-actuating mechanism provided with an operating member so arranged that the clamping jaws may be moved into clamping position in part by inertia imparted to the operating member, e. g., by means of an operating cable. The operating member may, for example, be a pivoted operating lever connected to an operating cable passing through a cable guide or ring located intermediate the extreme positions of the lever.

Still a further object is to provide a block-clamping frame provided with cooperating gripping jaws which is readily adjustable to accommodate blocks of different sizes, or rows of

blocks of variable numbers of blocks; and to provide a frame of the type described wherein the effectiveness of the clamping action does not depend upon the accuracy of the adjustment whereby the interval between the gripping jaws is controlled.

Another object is to provide a block lifter of the type described having a plurality of gripping jaws for clamping blocks arranged in a common frame, for effecting dependable clamping action despite irregularities in the blocks and/or the failure of some of the gripping jaws to function.

Still another object is to provide a block lifter of the type described having a plurality of gripping jaws, arranged on the same or on a plurality of block-clamping frames, having a simple mechanism for actuating all clamping jaws simultaneously.

Still further objects are to provide an improved block lifting and loading device which is adapted to be supported from an overhead monorail, bridge crane, wheeled vehicle or industrial type crane or similar device for lifting any desired number of blocks from a stack to another desired location, or to the same or another location with a different spacing between the blocks; to provide a device wherein the power required for clamping the jaws to the blocks and for unclamping the blocks is easily applied manually, and wherein the spacing between the blocks can be varied by the simple operation of rocking an operating lever; and to provide a loader which is dependable, simple to operate by comparatively unskilled personnel, and is of simple construction.

With these and other objects in view, which will become obvious in part and be pointed out in part in the course of the following description of the elements and applications of principles constituting the invention, reference is made to the accompanying drawings forming a part of the specification and illustrating a preferred specific embodiment of the invention, wherein:

Figs. 1 and 2 are a plan view and an elevation view, respectively, of my block lifting device;

Fig. 3 is a transverse sectional view, taken on line 3-3 of Fig. 2;

Fig. 4 is an elevation view of a part of the transverse block-clamping frame, corresponding to Fig. 3, portions being shown in section;

Fig. 5 is an enlarged sectional view of one side of the block-clamping frame, taken on line 5-5 of Fig. 2;

Fig. 6 is an enlarged sectional view taken on line 6-6 of Fig. 3;

Fig. 7 is an elevation view showing portions of the clamp-actuating mechanism in clamping position and, in dotted lines, in unclamping position;

Fig. 8 is a fragmentary sectional view taken on line 8-8 of Fig. 1, showing the spacing mechanism.

The block lifting device according to this invention comprises, briefly, a supporting structure adapted to be suspended and having a pair of longitudinal beams extending to both ends of the structure. A plurality of block-clamping frames are slidably suspended from these beams on each end of the center of the supporting structure. To vary the longitudinal spacing of these frames a space-regulating bar is provided for each end of the device, the two bars being connected by linkage at the center of the supporting structure so that they may be moved simultaneously toward the ends or simultaneously toward each

other. The space-regulating bars are fixed to the outermost block-clamping frames and connected to the other frames by lost motion arrangements permitting progressively increasing relative movement between the bar and the frames from the outermost frames toward the center, whereby movement of the bar causes a maximum movement in the outermost frames and progressively smaller movements in successive frames.

10 The block-clamping frames have depending legs which are laterally adjustable, whereby the transverse, horizontal interval between the legs can be adjusted. The legs carry movable gripping jaws having vertical engaging surfaces. The 15 jaws are mounted on the legs by supports which constrain the jaws to approach each other upon a movement of the jaws downwardly. Such support may be of any type, e. g., a parallelogram linkage or a simple sliding engagement with depending legs, which may, for this purpose, be convergent downwardly. In the preferred embodiment, described in detail herein, the supports are 20 in the form of cam pins extending through inclined cam slots in guides or flanges on the gripping jaws. Such jaws are brought into clamping position by their own weight, and, when the frame is lifted, the added weight of the blocks clamped between the jaws tends to force the jaws still further together. The jaws may be released 25 by lifting them relatively to the frame.

The clamp-mechanism comprises a longitudinal clamp-actuating bar on each side of the device traversing all frames and suspended by links from actuating levers. The several gripping jaws 30 are suspended from the clamp-actuating bar, whereby an upward movement of the bar releases all gripping jaws, and a downward movement of the bar permits all jaws to drop to clamping positions. For operating the actuating levers I may 35 use any operating arrangement; in the embodiment shown there are two operating levers rigidly connected to the actuating levers and extending from their pivot points toward the center of the device. They are arranged to have raised 40 clamped positions and lowered unclamped positions. A cable guide, in the form of a ring, is fixed on the supporting structure between the ends of the operating levers a short distance 45 above their unclamped positions; a connecting cable connects the ends of the operating levers, above the cable guide; and an operating cable extends through the cable guide, being connected to the middle of the connecting cable. With the 50 levers in their raised positions and the connecting cable almost taught, a powerful pull on the connecting cable can be effected by a relatively light pull on the operating cable to initiate the unclamping operation; continued tension moves the 55 levers to their lower positions, the last portion of their travel being by inertia, after passing the level of the cable guide. When in their lower, unclamping positions, the connecting cable is 60 looped up through the cable guide and extends downwardly to the ends of the operating levers; 65 a sharp tug of the cable lifts these levers, and inertia, together with the weight of the clamp-actuating bars and the suspended gripping jaws, causes the levers to continue their motion to their upper positions.

70 The invention will be better understood by reference to the drawings. Referring particularly to Figs. 1-3, reference number 20 represents the main, longitudinal supporting member, formed of an I-beam and connected to eyes 21 and 21a by which the entire lifting device may

be suspended from a hoist, crane, or the like. Transverse I-beams 22 and 22a are bolted to the ends of the supporting member 20 and are rigidly connected by main, longitudinal, tubular beams 24 and 24a, which extend throughout the length of the device and are welded to the I-beams 22 and 22a. The block-clamping frames are suspended slidably from the beams 24 and 24a. The parts described above form the supporting structure.

Six block-clamping frames are provided in the specific embodiment shown in the drawings, disposed in a longitudinal column, three in each end of the supporting structure. Each frame comprises two transverse inverted U-frames spaced apart longitudinally. One of the inverted U-frames is shown in part in Fig. 4, and the composite block-clamping frame is shown in Figs. 3, 5 and 6. Each inverted U-frame comprises: an intermediate, horizontal supporting section 25; side sections 26 and 26a forming vertical legs and having short horizontal arms; and a pair of horizontal tubes 27 and 27a. The intermediate section and the side sections are of cellular construction and the horizontal tubes 27 and 27a are mounted within these sections, being fixed to the intermediate section by means of bushings 28 welded thereto. Bushings 29, welded to the side sections, are slideable on the tubes 27 and 27a, whereby the side sections may be moved laterally to vary the horizontal interval between the legs. Sleeves 30 and 30a are fixed to the top of the section 25 and have sliding fits with the beams 24 and 24a, respectively.

The two inverted U-frames forming one block-clamping frame are joined by connectors 31 and 31a, each connector consisting of a pair of bars welded at their ends to the respective side sections and, at their intermediate portions, to internally threaded blocks 32. A tie rod 33 is in threaded engagement with the blocks 32 and has square ends. The threads at one end are right-handed and at the other end are left-handed, whereby the spacing between the side sections can be varied by turning the tie rod 33. A stop 34, fixed to the intermediate sections 25 by connecting bars 31b, prevents axial movement of the tie rod and thereby prevents the side sections from swaying laterally with respect to the intermediate sections. The side sections of the two inverted U-frames are, further, connected by angles 35 and 35a. Each of these angles supports two parallel sleeves 36 by means of horizontal supports 37 formed of bar metal welded to the sleeves and to the angles 35 or 35a. These sleeves are axially aligned with holes 38 in the vertical legs (see Fig. 4). Cam pins 39 extend through these holes and sleeves. Eight rollers 40 are rotatably mounted on each cam pin, there being one roller on each side of each sleeve 36 and one on each side of each leg. The six rollers between the frame legs are retained in position by three spacer bushings 41; those on the outside of the legs are retained by washers 42, secured in turn, by cotter pins.

Four gripping jaws 43 are slidably mounted on each side of the frame. Each jaw is provided with a vertical engaging surface carrying a coating of resilient or yieldable material 44, such as neoprene or other rubber-like material having a good wearing quality and a high coefficient of friction. The sides of the jaws are bent back away from the engaging surfaces and perpendicular thereto, forming guides or flanges 43a; these guides stiffen the gripping jaws and sup-

port them. The guides are reinforced by having their thickness doubled at levels opposite the cam pins 39. The two outer gripping jaws on each side of the frame are mounted with the inner faces of the guides 43a in sliding engagement with opposite sides of the frame legs; the two intermediate jaws have the inner faces of their guides in engagement with the ends of the sleeves 36. Inclined cam slots 43b are cut through the reinforced portions of the guides and have the widths necessary to accommodate the rollers 40. The cam slots are inclined to slope upwardly and outwardly (i. e., away from the engaging surface). They are inclined to the vertical at an angle smaller than the angle whose tangent equals the coefficient of friction of the block being lifted against the coating 44 or, in the case in which several blocks in a row are to be clamped together, the coefficient of friction of the blocks to each other, which ever coefficient is smaller. For example, in the embodiment illustrated, designed for handling concrete masonry blocks, the slope is four on one (approximately 14° to the vertical, corresponding to a tangent of 0.25). As a consequence of the upwardly and outwardly inclined cam slots the jaws on opposite sides of the frame move apart when they are raised and move toward each other when they are lowered.

The gripping jaws are held in their raised positions by a clamping mechanism, to be described. When thus raised, the frame is lowered over a block or a stack of blocks and the jaws are lowered. In the specific embodiment described herein, the jaws move downwardly by gravity upon being released by the clamping mechanism. They move downwardly until their engaging surfaces come into contact with a block. An initial clamping action takes place as the jaw is wedged between the block and the cam pin, the coating 44 being thereby compressed. It is, however, also within the purview of the invention to supplement the action of gravity by providing a spring or other means for urging the jaws downwardly and increasing the initial clamping action. When the frame is then raised the weight of the block or blocks tends to carry the gripping jaws still farther down and urges the jaws still closer together, thereby effectively clamping the block or blocks.

For best operation it is desirable to provide rollers 40 having a minimum of friction, although in certain instances, as when the materials handled have high coefficients of friction, such anti-friction rollers may be omitted. By providing a plurality of independently mounted gripping jaws on each side of the frame a good contact with the block is assured, despite irregularities in the shapes of the blocks. Moreover, it should be noted that it is desirable to maintain the engaging surfaces of the jaws on opposite sides of the frames parallel; in the embodiment described they are maintained vertical, and this is preferred, although not in every case essential. Maintenance of the parallel relationship during movement of the jaws is particularly desirable when vertical tiers of blocks, e. g., several superposed layers of bricks, are to be clamped. To achieve this the jaws are made to move together or apart in essentially translatory motion by providing a plurality of cams at different levels. It is, of course, not essential that the cam slots 43b be straight, as illustrated, since curved cam slots may be used; however, all cam slots should have essentially the same shapes and slopes, so that the jaws will move

without deviating from their vertical positions. Moreover, it is desirable to locate the holes 38 and sleeves 36 to make provision for deflection or deformation of the frame when placed under a load. Thus, when blocks are clamped the lower ends of the legs will be urged apart to an extent depending upon the horizontal thrust and the size of the frame. The extent of this deformation can be readily calculated by methods well known in the art, and the holes 38 and sleeves 36 are preferably located so that they are not in a truly vertical row when the frame is unloaded; instead, they are located farther inwardly progressively towards the bottom, so as to assume a vertical relationship when the frame is loaded. This slight departure from the vertical when the frame is unloaded is too small to be shown on the drawings. The correction for load deflection can, of course, be provided in other ways, e. g., by thickening the coating 44 toward the bottom, or by locating the cam slots 43b at varying distances from the engaging surfaces, or by modifying the shapes of the cam slots slightly. All of these are too small to be illustrated in the drawings. In many cases, however, it is not necessary to take such a precaution in design, particularly when the weight of the blocks is small in relation to the strength of the frame.

While I have shown the cam slots in the gripping jaws and the cam pins on the frame, it is evident that these may be interchanged by a simple mechanical modification.

The clamping mechanism comprises: A pin 45 fitted in holes in the upper portions of the guides of each gripping jaw and extending through a link 46; clamp actuating bars 47 and 47a; and levers for raising and lowering the bars. One bar is provided on each side of the device and extends through all of the links 46 on its respective side, whereby each clamp actuating bar supports twenty-four links. Transverse rods 48 and 48a are journaled in sleeves 49 bolted to the bottoms of the I-beams 22 and 22a, respectively. Actuating levers 50 are fixed to the rods 48 above each bar 47 and 47a and are pivotally connected by rigid, curved suspension links 51 to eyes in bands on the bars 47 and 47a. Each bar is, therefore, suspended at two, longitudinally spaced points. In the position shown in Figs. 2 and 6 the rods 48 and 48a, levers 50, links 51 and actuating bar 47 are in their raised positions. When the rod 48 is rotated counterclockwise and the rod 48a is rotated clockwise, the bar 47 is first raised slightly as the ends of the levers 50 pass through top dead center; thereafter they are lowered, permitting the links 48, pins 45 and gripping jaws 43 to descend by gravity.

Each of the rods 48 and 48a carries an operating lever 52 or 52a, fixed so as to extend toward each other and to be slightly downwardly inclined when in their unclamping position shown in Fig. 2 and in dotted lines in Fig. 7. The actuating lever 50 and operating lever form a bell crank. A connecting cable 53 connects the ends of the operating levers and has a length equal to the distance between the levers when in their raised, clamping positions, shown in solid lines in Fig. 7. A cable guide, in the form of a ring 54, is fixed to one of the block-clamping frames near the center of the device and is located between the ends of the operating levers within the sectors defined by their clamping and unclamping positions, but nearer to their unclamping positions. An operating cable 55 extends through the cable

guide and is secured to the center of the connecting cable 53.

When the gripping jaws are in their downward positions and loaded with blocks, the frame is lowered to support the blocks externally, e. g., on a truck platform or on other blocks, before unclamping them. With the blocks thus supported, and the operating levers in their clamping positions, the mechanism is operated by pulling on the operating cable 55. A relatively light pull on the cable will result in a considerably greater tension on the connecting cable, thereby rotating the operating levers toward each other. This large initial force is necessary because the gripping jaws are clamped to the blocks and must be lifted against the frictional resistance of the blocks to disengage them. Once the blocks have been disengaged the resistance to the motion of the operating levers is decreased, being opposed only by friction and weight of the parts, and the levers continue their motion, coming to rest in the positions shown in Fig. 2 (and in dotted lines in Fig. 7). It should be noted that the connecting cable is drawn partly through the cable guide during this action. It is, however, not pulled so far as to stop the operating levers when they come opposite to the cable guide, slack being left to continue to permit movement to their lowest positions shown.

When the parts are in the unclamping position they remain in that position because the actuating levers 50 have been rotated beyond top dead center, i. e., beyond the point at which the gripping jaws have been raised to their highest positions. To return the parts to the clamping positions the operating cable 55 is given a sharp tug or pull downward. This lifts the ends of the operating levers to the level of the cable guide. The levers then continue to move past the cable guide by momentum and by the weight of the gripping jaws and clamp-actuating bars, the actuating levers 50 having by this time moved beyond top dead center.

For moving the block-clamping frames longitudinally along the beams 24 and 24a I provide a pair of space-regulating bars 56 and 56a, one for each end of the device and traversing the three frames in the respective ends. Each space-regulating bar is fixed to the outermost frame by nuts 57 and has a lost-motion connection to the intermediate frames. The lost motion connections on each bar comprise sleeves 58 and 59 fixed to the respective bar and engageable with corresponding lugs 60 and 61, respectively, carried by the connectors 31b on the block-clamping frames. The lugs 60 and 61 have engaging flanges for alternate engagement with the ends of the sleeves 58 and 59. The play between sleeves 59 and lugs 61 on the innermost frames is greater than the play between sleeves 58 and the lugs 60 on the intermediate frames. For example, if the device is to be used to clamp six rows of blocks which have 2 inches of free space between the rows, each bar 56 or 56a will have a longitudinal travel of five inches, this being also the travel of the outermost frames; the intermediate frames will have a travel of three inches, and the innermost frames a travel of one inch; hence the play at the lugs 60 should be two inches, and at the lugs 61 it should be four inches. When the device is loaded with blocks which are fully spaced longitudinally and the bars 56 and 56a are moved inwardly, the outmost frames are pulled inwardly with them; when the sleeves 58 and lugs 60 come

into engagement, the intervals between the two outmost rows of blocks at each end of the lifter will have been closed, and both the outermost and intermediate frames are moved inwardly during the continued movement of the bars; finally, when the sleeves 59 and lugs 61 come into engagement, all three frames in each end are moved inwardly during the last inch of travel. When the reverse action takes place, the bars are moved outwardly and, initially, only the outermost frames move; then the sleeves 58 and lugs 60 are engaged and the intermediate frames begin their outward movement; finally, the sleeves 59 and lugs 61 are engaged and all frames move during the last part of the movement.

The space-regulating bars are actuated by links 62 and 63 pivotally connected to the bars 56 and 56a through eyes in flanges fixed to the sleeves 59, and to the ends of a double lever comprising parallel bars 64 and 64a, mounted on a transverse shaft 65. This shaft is journaled in the main supporting structure by sleeves 66 carried by a T-beam 70 welded to the beams 24 and 24a. The end of the shaft 65 carries an operating lever 67 having cables 68 and 69. By pulling on these cables the shaft 65 and the lever 64 may be rotated to move the bars 56 and 56a inwardly or outwardly to vary the longitudinal spacing of the frames.

I claim as my invention:

1. A device for lifting blocks comprising a frame providing a plurality of pairs of gripping jaws spaced apart horizontally and having parallel, vertical engaging surfaces, the jaws on at least one side of the frame being movable vertically with respect to said frame, each said movable jaw having a guide extending away from the engaging surface thereof and slidably guided by said frame, and a plurality of vertically spaced cam means supporting said movable jaws on the frame, each cam means having an upwardly and outwardly inclined cam slot and a cooperating cam pin, one on the frame and the other on said guide, for moving said movable jaws in translatory motion toward the other jaws of the respective pairs when said movable jaws move downwardly with respect to said frame.

2. A device for clamping blocks comprising a frame adapted to be moved in a direction of thrust for moving blocks in said direction, a pair of legs at opposite sides of said frame and extending generally in a direction parallel to said direction, said legs being rigidly connected and adjustable to permit the interval between said legs to be varied, a gripping jaw slidably mounted on each leg, said jaws having parallel engaging surfaces substantially parallel to said direction, and cam means between each of said legs and the corresponding jaw arranged to move each jaw toward the other jaw in essentially translatory motion upon a movement of the jaws with respect to the legs in a direction opposite to said direction of thrust.

3. A device for clamping blocks comprising a frame having a pair of substantially vertical legs, slide means at the upper ends of said legs arranged to maintain said legs rigidly at any selected horizontal interval, positioning means for adjusting the horizontal interval between said legs, a gripping jaw on each of said legs, said jaws having parallel engaging surfaces substantially parallel, at least one of said jaws being movable vertically with respect to its respective leg, said movable jaw being guidingly supported on its respective leg for movement toward the other

jaw upon a downward movement thereof while maintaining the parallel relationship between the engaging surfaces, and actuating means for raising said movable jaw with respect to the frame.

5. A device for lifting blocks comprising a frame having an intermediate supporting section and a pair of depending legs at the sides thereof, at least one of said legs being laterally movable to permit the horizontal interval between said legs to be varied, means for securing the legs at any desired interval comprising a tie rod connecting said legs and adjustably attached thereto, a gripping jaw movably mounted on each leg, said jaws having parallel, vertical engaging surfaces, and supporting means between each of said legs

10 and the corresponding jaw arranged to move each jaw toward the other jaw while maintaining the parallel relationship between the engaging surfaces upon a downward movement of the jaws with respect to said legs.

5. A device for lifting blocks comprising a frame providing a pair of depending legs on each side thereof, a movable gripping jaw for each of said legs, said jaws providing parallel engaging surfaces, each jaw having a guide extending away from the engaging surface thereof and slidably guided by the respective leg, a plurality of vertically spaced cam slots in each of said guides extending upwardly and outwardly, and cam

20 pins on said legs extending through said cam slots for supporting said jaws.

6. A device for lifting blocks comprising a frame providing a pair of depending legs on each side thereof, there being an interval between legs on the same side of the frame, a movable gripping jaw on each of said legs, said jaws providing parallel engaging surfaces, each jaw having a plurality of vertical guides extending away from the engaging surface thereof and slidably guided

35 by the respective leg, intermediate movable engaging jaws with parallel engaging surfaces between the gripping jaws on the legs on the same side of the frame, a plurality of vertical guides on said intermediate jaws extending away from the engaging surfaces thereof, a plurality of vertically spaced, upwardly and outwardly inclined cam slots in each of said guides on the intermediate jaws, and cam pins connecting the legs on the same side of the frame extending through the cam slots of the guides on the several jaws on the same side of the frame for supporting said jaws.

7. A block lifter comprising a supporting structure, a plurality of block-clamping frames disposed longitudinally along said structure, each of said frames providing a pair of cooperating gripping jaws spaced apart horizontally, at least one of said jaws on each frame being movable vertically with respect to said frame, a support for each movable jaw arranged to move said

50 movable jaw toward the other jaw in the same frame when said movable jaw moves downwardly with respect to said frame and away from said other jaw when said jaw moves upwardly with respect to said frame, and actuating means common to several longitudinally spaced frames having a clamping position and an unclamping position for raising the movable jaws on the several frames when moved to its unclamping position and for releasing said jaws for individual downward movement when moved to its clamping position, said last-named means comprising a longitudinal clamp actuating bar on the supporting structure, suspension means connecting said movable jaws to the clamp actuating bar, and means

for raising and lowering the clamp actuating bar.

8. A block lifter comprising a supporting structure, a plurality of transverse block-clamping frames disposed longitudinally along said structure, each of said frames providing a pair of cooperating gripping jaws with vertical, parallel engaging surfaces movably mounted in said frames, a plurality of vertically spaced cam means for each gripping jaw supporting the respective jaw on the respective frame, said cam means having an upwardly and outwardly inclined cam member and a cooperating cam pin, one on the jaw and the other on the frame, for moving said jaws in essential translatory motion toward each other when said jaws move downwardly with respect to their respective frames and away from each other when said jaws move upwardly with respect to their respective frames, and actuating means on said supporting structure common to several longitudinally spaced frames having a clamping position and an unclamping position for raising the jaws on the several frames simultaneously when moved to its unclamping position and for permitting individual downward movement of the jaws on the several frames when moved to its clamping position.

9. The block lifter according to claim 11 wherein the means for raising the jaws comprises a plurality of transverse shafts on the supporting structure, a longitudinal clamp actuating bar on each side of said structure connected by linkage to said shafts for simultaneous upward or downward movement of said bars, and suspension means connecting the gripping jaws to said clamp actuating bars.

10. A block lifter comprising a block-clamping frame having gripping jaws mounted for relative motion, and means for actuating said jaws comprising a movable operating member operatively connected to said jaws to decrease the interval between the jaws when the operating member is in its clamping position and to increase said interval when the operating member is in its unclamping position, a cable guide fixed intermediate to the clamping and unclamping positions of said operating member, and a cable extending through said cable guide and connected to said operating member.

11. A block lifter comprising a block-clamping frame having cooperating gripping jaws, at least one jaw being movably mounted on said frame, a support for said movable jaw arranged to restrain said movable jaw to approach the other jaw upon a downward movement of said movable jaw and to move away from said other jaw upon an upward movement of said movable jaw, and means for actuating said movable jaw comprising a pivoted actuating lever, linkage connecting said lever to said movable jaw for lifting said jaw, said lever having a clamping position in which the movable jaw is in its lowered position and unclamping position in which the movable jaw is in a raised position, the actuating lever being arranged to move beyond the position at which the movable jaw is lifted to its highest position when said actuating lever is moved pivotally to its unclamping position, whereby the weight of the movable jaw tends to hold the lever in its unclamping position.

12. In combination with the block lifter according to claim 14, an operating lever associated with said actuating lever and movable therewith to a clamping position and to an unclamping position, a cable guide fixed intermediate the clamp-

ing and unclamping positions of said operating lever, and a cable extending through said cable guide and connected to said operating lever.

13. A clamp-actuating mechanism for a block lifter having movable gripping jaws arranged to be unclamped when raised and clamped when lowered, comprising a pair of operating levers pivotally mounted on the block lifter and connected to said gripping jaws for lifting said jaws, said levers extending toward each other from their pivots and having raised clamping positions in which the gripping jaws are lowered and lowered unclamping positions in which the gripping jaws are raised, a cable guide fixed to the block lifter within the sectors defined by the clamping and unclamping positions of the said levers and near to the unclamping positions thereof, a connecting cable joining the free ends of the operating levers and having a length substantially equal to the distance between said free ends when said levers are in their clamping positions, and an operating cable extending through said cable guide and connected to an intermediate point on said connecting cable.

14. A block lifter comprising a supporting structure, a plurality of transverse block-clamping frames disposed in a longitudinal row and movable longitudinally on said structure, each frame providing a pair of cooperating gripping jaws at opposite sides of said structure and having vertical, parallel engaging surfaces, at least one of said jaws in each frame being movable to decrease or augment the interval between the jaws of the same frame, means for actuating said movable jaws on the several frames simultaneously, and means for varying the longitudinal spacing between said frames along said supporting structure.

15. The block lifter according to claim 14, wherein the means for varying the longitudinal spacing comprises a longitudinal space-regulating bar secured to one of said transverse frames and having a lost-motion connection to another of said frames.

16. A block lifter comprising a supporting structure, a plurality of transverse block-clamping frames disposed in a longitudinal row and movable longitudinally on said structure, each frame providing a pair of cooperating gripping jaws on opposite sides of said structure, said jaws having vertical, parallel engaging surfaces and being movably mounted on said frames for upwardly divergent and downwardly convergent movement, a longitudinal clamp actuating bar connected to said gripping jaws for lifting the jaws, and a longitudinal space-regulating bar for varying the longitudinal spacing between the frames on said supporting structure.

17. A block lifter comprising a supporting structure extending from a longitudinally intermediate point thereon to form two ends, a plurality of transverse block-clamping frames disposed in a longitudinal row and movable longitudinally on said structure, each frame providing movable gripping jaws for clamping blocks, means for actuating said jaws, a longitudinally movable space-regulating bar for each end of the supporting structure, each of said bars being connected to the several block-clamping frames on the same side of said intermediate point through a lost motion arrangement for moving successively more outlying frames progressively greater longitudinal distances as said bar is moved longitudinally, and means for moving said bars simultaneously outwardly or simultaneously

inwardly for increasing or decreasing, respectively, the longitudinal spacing between said block-clamping frames.

18. A block lifter comprising a supporting structure, means for suspending said structure from the center thereof, said structure having a plurality of supporting beams extending longitudinally from said center to form two ends of the structure, a plurality of transverse block-clamping frames longitudinally slidable on said beams on each of said ends, each frame providing movable gripping jaws for clamping blocks, means for simultaneously actuating the gripping jaws on a plurality of said frames, a longitudinally movable space-regulating bar for each of said ends of the supporting structure, each of said bars being fixed to the outermost block-clamping frame and traversing the other frames, engaging means on said bar for said other frames and cooperating stops on said other frames, said engaging means and stops being positioned to provide progressively more lost motion between

said engaging means and the stops on successive frames toward said center, a lever pivotally mounted near the center of the supporting structure rotatable about a transverse axis at a point intermediate to the ends of the lever, and links connecting each end of the lever to a different one of said space-regulating bars.
